UNITED STATES PATENT OFFICE.

LOYAL F. CRAWFORD, OF PITTSBURGH, PENNSYLVANIA, ASSIGNOR TO GOODMAN MANUFACTURING COMPANY, OF CHICAGO, ILLINOIS, A CORPORATION OF ILLINOIS.

MINING SYSTEM.

Application filed March 3, 1928. Serial No. 258,728.

This invention relates to improvements in mining systems, and more particularly to mining systems used for advancing double entries in relatively thin or low coal seams, 5 and has for its principal object to provide an improved form of apparatus and system for driving in advance development work as for instance, in room and pillar mines, whereby the requirement of a certain skilled labor or 10 ordinarily employed in similar operations is eliminated, brushing of the roof or taking of bottom and transportation of waste rock resulting therefrom is reduced to a minimum, and the problem of sufficient mine car supply 15 is effectively solved in connection with the use of portable mining and scraper loading devices so that the costs of production of coal in relatively low seams may be reduced sufficiently to enable such thin seamed coal mines 20 to be operated in competition with higher seamed coal mines.

It is well known that the constant demand for coal is causing a constant diminution of the available supply in the mines where the 25 coal measures are thick or high enough to permit the use of standard mining apparatus and transportation facilities including mine cars, without requiring the removal of excess rock above or below the haulage ways and 30 mine tracks. Such relatively high coal measures are generally termed "high coal" of which the minimum height is usually considered to be about three and one-half or four feet. The diminution in the available supply of such 35 "high coal" has resulted in an increasing development of relatively "low coal" mines, where the coal seams are less than three and one-half to four feet in thickness, although the costs of coal extraction naturally tend to 40 exceed the costs of extraction of the higher coal on account of the added difficulties imposed by low roof conditions. In some instances the added cost of mining low coal is partially offset by the fact that the coal is 45 of better grade, or that the mine is nearer the point of consumption than a competing high coal mine, but in every case the successful operation of relatively low coal mines depends mainly upon the development of a 50 highly improved economical mining system which will enable such mines to overcome their inherent disadvantages and compete upon a fairly equitable basis with high coal mines.

Accordingly, it will be borne in mind, in

connection with the following description of my invention, that the improved mining system and apparatus has been developed with especial reference to the difficulties imposed by low roof conditions, where at least a 60 portion of the rock roof or floor must be removed to permit the use of standard equipment including mine cars of standard height, although it will be understood further that many of the features herein disclosed are 65 not necessarily limited to low roof conditions but may also have general application to other systems of mining.

The invention may best be understood by reference to the accompanying drawings in 70 which:

Figure 1 is a plan view of a double entry advance development, with parts of the entries broken away at certain points as indicated, and showing the arrangement of the 75 tracks in one stage of development;

Figure 2 is a view similar to Figure 1 but showing the advance work in another stage of development with the coal cutting and loading apparatus in operative position and 80 with a string of mine cars on the tracks;

Figure 3 is a vertical section taken on line 3—3 of Figure 2;

Figure 4 is a vertical section taken on line 4—4 of Figure 2;

Figure 5 is a view similar to Figure 2 but showing a cutting and loading apparatus in a further advanced stage of operation;

Figure 6 is an enlarged detail view of an improved form of a portion of track made up 90 in detachable sections, which is utilized as a part of my improved mining system;

Figure 7 is a view of another portion of track forming a part of my improved mining apparatus;

Figure 8 is a view similar to Figure 5, showing an alternative intermediate step of mining out a complete break through from one extended entry before work is begun upon the adjacent entry; and

Figure 9 is a view similar to Figure 8 showing the alternative intermediate step in further stage of advancement with mine tracks installed.

Referring now to the details of the mining 105 system shown in the drawings, it will be understood that the principal object of the system therein shown is to advance a pair of entries 10 and 11, arranged in parallel relationship to each other and separated by a 110

series of pillars 12, 12, having a plurality of break throughs 13, 13, forming transverse passageways at certain intervals between the parallel entries 10 and 11. The entries are 5 driven in pairs in the usual manner so as to provide incoming and outgoing air passages forming part of the general ventilation system of the mine. The several break throughs 13, 13, also form a part of the ventilation 10 system as required during the advance developmental work, as well as providing communication between adjacent entries for transportation purposes. The width of the entries 10 and 11 may vary somewhat depending upon 15 the local conditions but with the preferred system herein illustrated they are of sufficient width for track haulage as well as turning radius on the track curves, for which purposes the entries should be in the neighborhood of 20 twenty-four feet in width. The width of the pillars 12, 12, may also vary, depending upon local conditions, in the illustration shown the pillars being approximately sixteen feet in width. The length of the pillars, determined 25 by the distance between the break throughs 13, 13, is preferably as great as possible commensurate with requirements for ventilation during advancing work, and also to permit the use of relatively long stretches of track as 30 storage space for mine cars during loading operations. In many States of the Union, the cutting of break throughs within certain defined limits of advance development is mandatory either by statute or mine regulations, 35 these limits ranging from one hundred to three hundred feet, provided that auxiliary ventilation means be utilized, as will herein-after be described in greater detail. In carrying out my invention, I find it preferably to 40 make the distance between the break throughs as long as permissible by law, a distance of two hundred to three hundred fifty being found preferable where local regulations and gas conditions permit.

45 The advancing of the two entries 10 and 11 from one break through 13 to the next represents one complete cycle in the driving operations.

In order to describe a complete cycle of operations, it will be necessary to refer generally 50 to some of the more important features of arrangement of the entries, break throughs and trackage layed out during previous cycles of operation. Thus in Figure 1, a haulage track 14 extends up one of the entries as for instance, the entry 11, adjacent its outer wall, which entry has, as shown in Figure 4, had its height increased over the normal height 55 A—B of the coal measure by a distance sufficient to give clearance over the mine cars, as indicated at A—C. The waste rock material, which in the system illustrated herein is taken or "brushed" from the roof, has been previously disposed in areas indicated at 12^a, 12^a, 60 65 at the opposite sides of the pillars 12, these

areas being generally referred to as "the gob". These areas are preferably surrounded and defined by rows of mine props 12^b, of the usual type adapted to assist in supporting the roof adjacent the brushed areas. The haulage 70 track 14 extends forwardly to and through the last break through 13 and is looped backwardly through the opposite entry 10 and the next to the last break through 13, where it again connects with the main haulage track 14 as 75 clearly shown in Figure 1, thus forming a continuous loop about the next to the last chain pillar 12, as indicated generally by the numeral 15. This track loop 15 is preferably made up of a plurality of detachable track 80 sections, as will hereinafter more fully appear. For the present description it is sufficient to call attention to the two stub tracks T^o and T¹¹, disposed on opposite sides and closely parallel to the last pillar 12, beyond 85 the loop 15. These track stubs are utilized for placing of the cutting and loading apparatus as will presently be described.

The portions of the roof immediately above the break through 13 and the stubs T^o and T¹¹ are also brushed to a height greater than the normal height of the coal seam A—B, as indicated at A—C in Figure 3. A loading chute 23, forming part of the loading apparatus, is shown as mounted on the truck section 95 T¹¹.

The working faces of the two entries, i. e., the faces which are to be advanced in order to prolong the entries, are indicated at 16 and 17 respectively, and in the preferred form to 100 be herein described are each about twenty four feet wide. These working faces 16 and 17 are disposed about fifty feet in advance of the last break through 13, in order to provide a sufficient lead for the scraper loader cables, as 105 will presently appear. It will be understood of course, that the lines along which mining operations are advanced, and the distances between the points such as break throughs, track centers, etc., have all been previously determined upon and laid out by careful survey. 110

With the arrangement of trackage and developmental work in the stage shown in Figure 1 the necessary undercutting and loading devices are brought into the mining area on the haulage track 14. In the form shown the apparatus referred to includes an undercutting machine 20 of the shortwall type and a truck 21 from which said machine is removed 115 while cutting in the usual manner; a mining drum hoist 22, preferably mounted on wheels so as to be readily dragged over the mine floor or transported on a truck on the rails as required; a scraper loading outfit including a portable loading chute 23 having self-contained power devices thereon, and a scraper apparatus of the above well known form 24 used in connection with said loading chute; a power drill for forming powder holes; and a ventilating blower fan 26 equipped with 120 125 130

several lengths of flexible tubing 27 of sufficient length to be extended to the working face so as to displace with fresh air any smoke or gases encountered during the cutting, shooting and loading operations in the closed ends of the two entries.

The portable hoist 22 is suitably disposed at one side of track stub T¹¹ in line with the main haulage track 14, as shown in Figure 2, and is remotely controlled from the scraper loading chute 23 by the scraper loader operator. The undercutting machine 20 is run to the end of one of either one of the stubs T⁹ or T¹¹ where the initial cutting operations are to be commenced, in the form shown in Figure 2, the lower entry 11 being chosen for this purpose. The cutting apparatus is unloaded from the end of stub T¹¹ by taking the mining machine off its truck 21 and then placing the truck 21 at one side of the stub T¹¹ as for instance, closely adjacent the pillar 12, as shown. The loading chute 23 is then put into loading position on the stub T¹¹ so as to discharge loads of material brought thereupon by the scraper 24 into mine cars suitably positioned upon the main loop 15, as shown in Figures 2 and 3.

A string of empty mine cars, commonly termed a "trip", is brought into the mine along the haulage track 14 and around the forward end of the loop 15 into the opposite entry 10. Since this loop 15 is relatively long, that is, from two hundred to two hundred fifty feet or more, said loop provides sufficient storage for a large number of empty cars.

Cutting operations are commenced along approximately one half of the width of the working face 17, by use of the undercutting machine 20, which cuts a kerf in the usual manner extending approximately twelve feet in length from the wall or rib of the pillar 12, and to a depth of approximately seven feet. Thereafter the coal overlying this undercut portion is drilled, shot down, and loaded into the scraper 24 at the working face, from whence it is conveyed to the mine cars and loaded thereon over the inclined chute 23, in the usual manner. The loading out of one undercut portion, as described, forms a new working face 17^a substantially twelve feet in length as indicated in Figure 2. This working face is again undercut, shot, and loaded out with the scraper and this operation is repeated until a narrow entry about twelve feet wide is extended the full depth to which the entry is to be advanced in one stage, that is, up to the next predetermined break through 13^a (a distance of about two hundred to two hundred fifty feet), and about fifty feet therebeyond, as indicated by dotted lines 17^b, 17^b, indicating the side walls of the first-mined area, and 17^c the end wall of this mined area.

It will be understood of course, these last

named mining operations contemplate only the removal of the coal at the height of the coal measure, as indicated by the letters A-B, in Figures 3 and 4, the scraper 24 being operated in this relatively low-roof area.

At this stage only one-half of the full width of one entry has been mined. The remaining half is then mined out by making a series of undercuts along the outer side wall 17^b for the full length of the previously advanced narrow portion, as indicated in Figure 2. For this purpose an ordinary short-wall machine having a cutter bar of six to seven feet in length can cut to the full width of the room in two successive slabbing cuts. After each cut of course, the coal is shot down and loaded out by the scraper 24. In this case however, the scraper is movable longitudinally of the pile of loose coal shot down from the face, as clearly indicated in Figure 5, which indicates the position of the loose coal on the floor after one slabbing undercut has been made and the face prepared for loading. It is manifest from this figure that the second slabbing cut following the loading out of the loose coal from the first cut would complete the undercutting for the full predetermined width of the entry 11, and the loose coal shot down after the second undercut can also be loaded out by means of the scraper. In order to control the movement of the scraper during the loading operations where the scraper is moved in a line off-set from the center line of the loading chute 23, as shown in Figure 5, I prefer to use a scraper apparatus including a third rope control line 30 having a sheave 31 which engages the pulling rope 32 of the scraper. This third rope control loading apparatus, with control drums mounted beneath the chute 23, is well known in the art, and need not be described in detail. In the system herein described, a guide sheave 33 is carried on a jack 34 suitably anchored adjacent the rib in the far corner of the working face 17 and the outer wall or rib of the entry 11, as shown in Figure 5, and the path of movement of the scraper 24 may thus be controlled by shortening or lengthening the third rope control line 30 as desired. I also find it preferable to provide an auxiliary deflector 35, which may be of any suitable form, adjacent the outer side of the chute 23, in order to assist the movement of the scraper when it is approaching the chute at an angle. In the form shown this deflector 35 may consist of an ordinary length of track rail anchored by jacks 35^a, 35^a.

The purpose of providing an initial fifty foot advance of the entries 10, 11, beyond each break through 13 will now be understood when attention is directed to the desirability of providing a relatively long lead between the loading chute 23 and the control line 30 so that the scraper may always approach the loading chute at a relatively small

angle. In practice, a lead of about fifty feet is found best suited where the width of the entry is about twenty-four feet.

The opposite entry 10 may now be mined out in a similar manner, beginning with a narrow tunnel one-half the entry width and formed in line with the track stub T^o along the pillar 12. It will be understood however, that either entry may be mined out first, as desired. At any suitable time after the point of the next break through 13 has been reached, said break through may be cut through as for instance, from opposite sides of the pillar, although under many conditions, as an intermediate step of the method it may be found preferable to utilize the alternative method shown in Figures 8 and 9, as will be hereinafter more fully set forth.

During the loading operations above described the cars may be moved by means of the portable hoist 22 and cable along the track and outwardly toward the main line 14 as fast as they are loaded. The loaded cars may be hauled from the mine by means of mine locomotives at any desired interval without causing any delay in the cutting and loading operations.

When both entries have been developed to their full widths and have a uniform line of advance fifty feet beyond the next break through 13^a (in line with lines 17^c of Figures 2 and 5) the two entries are then prepared for advancing the track loop 15 to a new position, with the forward end of one loop extending through the new break through 13^a. The mining apparatus, including the cutting machine, scraper loading apparatus, etc., are withdrawn to a suitable position removed from the advance area, and the work of bringing up the tracks proceeds as follows:

Where, as in the typical conditions illustrated, the mined area beyond the last break through 13^a is of such limited height as to prohibit the use of mine cars therein, it is necessary, as the next step, to brush the roof or take bottom along the new layout for the track loop, so as to increase the height A—B to height A—C through the new break through 13^a and along the outer walls of the two entries 10 and 11. In the preferred method shown the necessary height is obtained by brushing the roof. The waste rock resulting from this brushing work is thrown over and disposed in the new gob area 12^a as close to the center lateral pillar as practicable.

The surveyor then lays out a series of sight lines and location points by means of which the position of the track can be located, these sight lines and points being most conveniently marked upon the roof of the mine, as for instance, as indicated at P¹, P², P³ and P⁴, etc., in Figure 1. The hoist 22 is dragged forwardly along on track or bottom of either

of the entries 10 and 11 to a new position just beyond the last break through. In Figure 1 said hoist is shown in full lines in the lower entry 11 substantially in line with the points P¹ and P² which mark the center line of the main haulage track 14. The hoist is preferably advanced to this position under its own power by anchoring the free end of the cable and dragging said hoist over the mine bottom to its new position. With the hoist in such position, the several sections of the track loop 15 are then detached from each other, and the sections disposed in the two entries are dragged forwardly to their new positions by means of the hoist cable.

Details of construction of certain typical track sections are shown in Figure 6, which is an enlarged view showing three sections T⁷, T⁸ and T⁹, forming the switch connections from the main track to the stub track T^o. Figure 7 illustrates the details of another combination of track sections T³ and T⁴, together constituting a single curve radius at one corner of the track loop 15. As will be seen from these figures, as well as from the general layout illustrated in Figure 1, the several track sections are arranged so that they may be taken apart, drawn forwardly to a new position along their respective entries and replaced with the aid of sighting points P¹, P², P⁴, etc., without the necessity of employing skilled track layers, the sections being provided with exact location marks, as for instance, point P⁵ of sections T³ and T⁴ (see Figure 7) so that said sections may be readily relocated by dropping a plumb line from the corresponding point P⁵ previously located by the surveyor on the roof of the mine. Similarly, other sections of the track are provided with point marks, such as P¹, P², P⁴ and P⁶, so that the track sections may be all readily located and connected in their new positions.

It will be observed further that the several track sections are suitably marked and fitted together in such a manner that they can only be rejoined together in proper order. For instance, sections T³ and T⁴, which otherwise might be similar to sections T⁵ and T⁶, are distinguishable by a different position of their respective location points P⁵ and P⁶ so that these two curve sections are readily identified and put in their proper positions. Similarly, the switch made up of parts T⁷, T⁸ and T⁹, shown in detail in Figure 6, is of different curvature from the switch section made up of parts T¹⁰ and T¹¹ and are further identified by means of the location points P⁴ and P⁶. It will be understood of course that the specific arrangement and proportions of the several divisions of track sections may be varied somewhat from that illustrated herein, as well as the specific arrangement of predetermined location points applied thereto, but I consider it to

be novel to provide a track loop made up of a plurality of track sections which may be detached and replaced in an advanced position with the aid of predetermined location 5 points, as herein disclosed.

It will be understood of course, that the hoist 22 which is used to draw up the separate sections of track, may be located in either entry and the track sections moved by 10 means of the cable and various arrangements of guide sheaves therefor, as are necessary. Thus, in Figure 1, the hoist is shown in full lines in entry 11 and in another possible position (in dotted lines) in entry 10.

15 After the track has been relocated and carried forward to a new position as shown in Figure 1, it is usually desirable to set the posts or props 12^b around the gob areas 12, 12, so as to support the roof along the brushed 20 trackway as shown in Figures 3 and 4. With the track laid and posts set as described, a full cycle of mining operations will then have been completed, ready for bringing the mining apparatus in for a new cycle of cutting and loading operations in order to advance the working faces 16 and 17 as before.

Figures 8 and 9 show an alternative step 30 in the method of advancing the entries 10 and 11 which may be used to speed up production under favorable conditions. In mining out the advance breakthrough 13, from entry 11, instead of stopping at the mid-point of the pillar 12 as has been above described (see Figure 5) said breakthrough is 35 extended through the pillar 12 to a point about twelve feet beyond from said pillar, which is equal to the width of the initial development tunnel as is illustrated at 17^c, Figure 2. After said breakthrough and extension thereof has been cut and the loose coal has been removed therefrom by means 40 of the scraper 24 in the usual manner, a nest 13^c is formed at right angles to the breakthrough 13 in an advancing direction. The loose coal is again removed from the next 45 13^c by means of the scraper 24 in the usual manner as illustrated in Figure 8. It should be noted that when removing material from the breakthrough 13 and nest 13^c that the 50 scraper 24 is loaded by hand where it is not possible for said scraper to gather its own load, and that the control rope 31 enables the scraper to turn from the breakthrough to the heading 10 at right angles thereto so 55 said loose coal may be loaded in the mine cars in the usual manner as has hereinbefore been explained.

The breakthrough 13 and nest 13^c being 60 mined out, the tracks 14 are extended and a curve is laid to said breakthrough. An extra section of track T¹⁵ is laid into said breakthrough. The curve is made up of switch sections T¹⁰ and T¹¹ exactly the same as the sections T¹⁰ and T¹¹ is placed at the preceding 65 break through 13 laid in the same man-

ner as said preceding sections by aid of a similar set of sights. After this track has been laid the top is shot down and the rock loaded on mine cars and hauled away. Simultaneously with the extension of the 70 track 14 and shooting and loading of rock from the breakthrough 13 and nest 13^c, the heading 11 may be advanced in the same manner as the heading 10 is advanced and as has hereinbefore been described, so that when said 75 heading connects with the breakthrough 13 and nest 13^c the rock has been removed from the top in said breakthrough and next to make headroom for mine cars and the scraper loader apparatus 23.

This alternative system, while requiring additional sections of track and a crew of men to shoot and load the rock while the opposite entry is being cut, is particularly advantageous in that it provides a means where- 80 by the rock work in one entry and breakthrough may be completed while the other entry is being mined out and thus it eliminates delays which would necessarily result if each entry or heading were to be mined out 90 and the top brushed separately. From the above described mining system and apparatus used it will be seen that several novel and advantageous features deserve especial emphasis. Among these features may be mentioned the following, in the order in which they appear in the cycle of operations just 95 described:

1. The initial cutting and loading operations advancing in limited width along the 100 inner sides of the entries 10 and 11 and adjacent the center pillar 12 affords several advantages. On account of the comparatively limited width of the initial penetration, the danger of roof falls are correspondingly limited until after the initial entry is widened out by the longitudinal slabbing cuts. When any roof falls occur adjacent the pillar they are not likely to seriously interfere 105 with the cutting and loading operations as such rock as does fall from the roof adjacent the pillar can be placed in the gob area 12^a with one handling and therefore does not require a second handling. A further advantage of this method is that it provides a relatively long working face for the two or more slabbing cuts (two or three hundred feet in length) which can both be cut and loaded out more rapidly than if the entire length of the working faces 16 and 17 were advanced in 110 one operation.

As a rule any bad roof has a tendency to 115 show up more quickly near the ribs of the entry while cutting the narrow tunnel and will develop and fall when these longitudinally extending slabbing cuts are made, but even if roof does fall it can be disposed of in gob area 12^a without rehandling. This slabbing cut also gives a cleaner and straighter side rib or wall than would be the 120 125 130

case if the entire width of the entries 16 and 17 were advanced by a series of relatively short advance cuts as in ordinary shortwall operations.

- 5 2. The use of a scraper loader gives particularly advantageous results in the economical operation of my improved system due to its adaptability to low roof conditions, and particularly where the third rope control line 10 30 is used for controlling the path of movement of the scraper along the coal face and cleaning up the loose material from the slabbing cuts along the outer walls of the entries. 3. The use of a complete track loop 15 extending through adjacent breakthroughs and providing ample storage space for cars which serves equally the loading apparatus in both entries, is also particularly advantageous inasmuch as this arrangement permits the cars to be handled by means of a single hoist and cable without the necessity of a separate locomotive for switching or moving the cars as they are being loaded. This arrangement of loop track ordinarily gives 25 storage space for enough mine cars to handle all of the coal loaded out during one shift or period of working hours so it is not necessary to couple up the haulage locomotive more than once in an entire shift for the purpose of transporting loaded coal away from the area of mining operation. In short, this improved track system aids in solving one of the chief shortcomings inherent in most mining systems, viz, that of providing a sufficient and constant supply of empty cars so as to permit substantial continuous operation of the cutting and loading apparatus. In my improved system employing a looped track, the loading operations are therefore entirely 35 independent of any of the delays usually occurring in the transportation of haulage systems for supplying entries or removing loaded cars from the area of mining operations. 4. The arrangement or layout of advancing development including the gob area 12^a, immediately adjacent the center pillar 12 is also of considerable importance in the economies claimed for the use of my improved mining system inasmuch as it entirely eliminates the necessity for transporting waste rock removed by brushing, etc. In my improved system this rock is deposited in the gob areas immediately to one side of the brushed areas, and therefore does not have 50 to be transported in mine cars for proper disposal. This saving in labor and transportation costs alone represents a substantial item ordinarily added to the cost of low coal extraction. 60 5. It will be observed further that especial provisions are made for safety of the miners, through the several stages of the operations above described. 65 6. This system of development is usually worked on the night shift as loading machines

can be worked without the extra cost of a motorman and helper to handle the cars since said cars may be placed in the loop during the day shift and these cars will be ample to run the night shift.

I claim as my invention:

1. In a coal mining and loading system, the method of advancing a pair of parallel entries on opposite sides of a pillar with breakthroughs connecting said entries at predetermined intervals, which consists in driving an initial tunnel along the inner side of one of said entries at a width substantially less than its final width, said initial tunnel extending substantially beyond the next predetermined point of breakthrough, and widening said initial tunnel along its outer face to its full width, then driving an initial tunnel of similar width and length in the adjacent entry, and widening the same in a similar manner along its outer face, extending and placing portable continuous loop track around said pillar and through the next advance breakthrough by means of predetermined sight points and loading loose material from both entries into mine cars stored on said loop track during the next succeeding cycle of advancing said entries.

2. In a coal mining and loading system, the method of advancing a pair of parallel entries on opposite sides of a pillar with breakthroughs connecting said entries at predetermined intervals, which consists in driving an initial tunnel along the inner side of one of said entries at a width substantially less than its final width, said initial tunnel extending substantially beyond the next predetermined point of breakthrough, and widening said initial tunnel along its outer face to its full width, then driving an initial tunnel of similar width and length in the adjacent entry, and widening the same in a similar manner along its outer face, brushing or removing rock from the roof of the mine in each of said entries along its outer wall and depositing said rock directly in a gob area along the side of the adjacent pillar, extending and placing portable continuous loop track in the brushed portions around said pillar and through the next advance breakthrough by means of predetermined sight points, and loading loose material from both entries into mine cars stored on said loop track during the next succeeding cycle of advancing said entries.

3. In a coal mining and loading system, the method of advancing a pair of parallel entries on opposite sides of a pillar with breakthroughs connecting said entries at predetermined intervals, which consists in driving an initial tunnel along the inner side of one of said entries at a width substantially less than its final width, said initial tunnel extending substantially beyond the next predetermined point of breakthrough, and wid-

ening said initial tunnel along its outer face to its full width, the loose material from said initial tunneling and widening operations being removed and loaded on to mine 5 cars by a scraper loader arranged for movement longitudinally of said entry, then driving an initial tunnel of similar width and length in the adjacent entry, and widening the same in a similar manner along its outer 10 face, extending and placing portable continuous loop track around said pillar and through the next advance breakthrough by means of predetermined sight points and loading loose material from both entries into 15 mine cars stored on said loop track during the next succeeding cycle of advancing said entries.

4. In a coal mining and loading system, the method of advancing a pair of parallel 20 entries on opposite sides of a pillar with breakthroughs connecting said entries at predetermined intervals, which consists in driving an initial tunnel along the inner side of one of said entries at a width substantially 25 less than its final width, said initial tunnel extending substantially beyond the next predetermined point of breakthrough, and widening said initial tunnel along its outer face to its full width, the loose material from 30 said initial tunneling and widening operations being removed and loaded on to mine cars by a scraper loader arranged for movement longitudinally of said entry and loading at a single point adjacent the pillar, then 35 driving an initial tunnel of similar width and length in the adjacent entry, and widening the same in a similar manner along its outer face, extending and placing portable continuous loop track around said pillar and 40 through the next advance breakthrough by

means of predetermined sight points and loading loose material from both entries into mine cars stored on said loop track during the next succeeding cycle of advancing said entries.

5. In a coal mining and loading system, the method of advancing a pair of parallel entries on opposite sides of a pillar with breakthroughs connecting said entries at predetermined intervals, which consists in driving 45 an initial tunnel along the inner side of one of said entries at a width substantially less than its final width, said initial tunnel extending substantially beyond the next predetermined point of breakthrough, and widening 50 said initial tunnel along its outer face to its full width, cutting the next breakthrough and extending it over a limited area in line with the opposite entry, brushing or removing rock from the roof of said mine 55 in an area along the outer wall of said first entry and through said breakthrough, extending a length of track along such brushed areas for loading out further advance work along said first entry while proceeding to 60 drive an initial tunnel of similar width and length in the adjacent entry, and widening 65 the same in a similar manner along its outer face, extending and placing portable continuous loop track around said pillar and 70 through the next advance breakthrough by means of predetermined sight points and loading loose material from both entries into mine cars stored on said loop track during 75 the next succeeding cycle of advancing said entries.

Signed at Chicago, in the county of Cook and State of Illinois, this 4th day of February, A. D. 1928.

LOYAL F. CRAWFORD.
